UNITED STATES PATENT OFFICE.

CHARLES L. PETERS, OF MARINETTE, WISCONSIN.

STAMP-AFFIXING DEVICE.

No. 927,749.

Specification of Letters Patent.

Patented July 13, 1909.

* Application filed April 30, 1908. Serial No. 430,053.

To all whom it may concern:

Be it known that I, CHARLES L. PETERS, a citizen of the United States, and resident of Marinette, in the county of Marinette and 5 State of Wisconsin, have invented certain new and useful Improvements in Stamp-Affixing Devices; and I do hereby declare that the following is a full, clear, and exact description thereof.

10 The object of my invention is to provide a simple and effective device for affixing stamps to envelopes, cards or like articles, its construction and arrangement being such that stamps with their gum-side up are fed from 15 a continuous strip to an anvil and moistened. An envelop or card is then placed in position over the moistened stamp, and said stamp is severed from the strip and simultaneously pressed upon the inserted article by a suitable die-block. This entire operation is 20 accomplished by the down-stroke of a manually-operated plunger, the upstroke of which plunger serving to impart motion to a train of gears in connection with a feed-mechanism, whereby another stamp is fed to the 25 anvil.

The invention therefore consists in various details of construction and combination of parts as hereinafter fully set forth with reference to the accompanying drawings and 30 subsequently claimed.

In the drawings: Figure 1 represents a sectional elevation of a stamp-affixing device embodying the essential features of my invention, the plunger being shown slightly depressed in order to illustrate the stamp-moistening roller in position upon the anvil, which position it assumes in passing over a stamp from the moistening-pan; Fig. 2, a front elevation of the device with portions broken away and in section to better illustrate the details, the parts being all in their normal position and at rest; Fig. 3, a plan sectional view of same, the section being indicated by line 3—3 of Fig. 1; Fig. 4, a detail cross-section of the feeding-mechanism, the section being indicated by line 4—4 of Fig. 1, and Fig. 5, a detail elevation of a backing-ratchet mechanism and hand-button 50 for actuating the feeding-mechanism.

Referring by numerals to the drawings, 1 indicates a base having parallel standards 2 secured thereto, which standards are connected by an upper bridge-piece 3, a pair of 55 forward bridge-pieces 4 and a stay-rod 5 to rear of said standards. The upper bridge-

piece 3 is centrally bored and serves as a guide for the shank portion of a plunger 6 having a flat slotted extension, which extension is provided with a series of rack-teeth 7 at its lower end. The extension of the plunger is also guided by a pin 8 that passes through the slot therein and is secured to the standards, there being suitable collars secured to the pin adjacent the sides of said 65 plunger-extension, whereby lateral play thereof is obviated. A head 9 is secured to the upper end of the plunger-shank, between which head and the bridge-piece 3 is inserted a coil-spring 10 that encircles said 70 plunger shank. The coil-spring serves to retract and hold the plunger in normal position, the upward stroke thus attained being limited by a collar 11 constituting part of the plunger-extension, which collar abuts on 75 the lower face of the bridge-piece. The rack-teeth 7 of the plunger are meshed with a mutilated pinion 12 having a shoe 13, which shoe is adapted to abut the face of the plunger-extension above the rack-teeth there- 80 of when said plunger is on its downward stroke. The shoe when resting upon the face of the plunger-extension serves to hold the pinion in position to be engaged by the rack upon the return-stroke of the aforesaid 85 plunger.

The pinion is secured to a spindle 14 revolvably mounted in the standards, the spindle having also secured thereto a gear-wheel 15, which gear-wheel is meshed with an idle gear-wheel 16 mounted upon a stud 18 supported in said standards, there being a flat-spring 18^a adapted to exert pressure upon the stud to insure steady rotation thereof. The idle gear-wheel 18 is in turn meshed with a gear-wheel 19 fast on a shaft 20, which shaft is revolvably supported by the standards and has loosely mounted thereon a drum 21. One end of the drum is provided with a ratchet-face 22 for engagement with a pawl 100 23, which pawl is pivoted to the gear-wheel 19 and is held in engagement with the ratchet-face by a spring also carried by said gear-wheel. The opposite end of the drum has a sleeve 24, which projects through a 105 bearing aperture in the adjacent side-standard, and is provided with a ratchet-wheel 25 having a hand-button 26 extending therefrom. This ratchet-wheel is engaged by a spring-pressed pawl 25^a which is mounted 110 upon the side standard and prevents overthrow or back-motion of the drum when the

latter is actuated by the gear-train to impart a forward-feed to the strip of stamps. Located directly under the drum 21 is a spool 27, the base 1 being recessed to permit the face of the spool to project therethrough and impinge against the lower face of said drum. The spool-spindle is hung in ears 28 that are fast on the arms of a flat-spring 29 secured to said base, the spring being supplied to exert 10 a yielding-contact between the gripping-surfaces of the aforesaid drum and spool, whereby the strip of stamps is fed forward.

Immediately forward of the feeding-mechanism just described, the base is provided with a cross-groove 30 and also a counter-sink, into which latter is flushly fitted a shear-plate 31 as best shown in Fig. 1 of the drawings. This shear-plate is alined with a knife 32 having an oblique cutting-edge, the knife being carried by a die-block 33, which die-block has a pair of upwardly extending guide-rods 34 that are reciprocative in apertures of the bridge-piece 4. Encircling each of these guide-rods between the lower bridge-piece and collars 35 secured to said guide-rods are spiral-springs 36, which springs serve to return the die-block when the latter is forced downward. The said die-block projects in the path of travel of the end of the plunger-extension, which end is adapted to engage the aforesaid die-block and force the same downward as the plunger is depressed, the engagement taking place approximately midway of the downstroke of said plunger. That portion of the base directly under the die-block constitutes an anvil 37 upon which the envelop or card desired to be "stamped" is placed. The standards directly above the anvil are cut away to serve as edge-guides for 40 said envelop or card, while a gage-plate 38 limits the forward end-thrust thereof, the gage being secured to said anvil. As shown in Figs. 1 and 2 of the drawings, the base between the side-standards and to the rear of the feed-mechanism comprises a table upon which the strip of stamps is adapted to slide, and with this in view the said base-portion is provided with a longitudinal spacing-strip 39 upon which a cover-plate 40 is secured by suitable screws, the rear end of the cover-plate being slightly upturned to facilitate the insertion of the strip of stamps thereunder.

The stamp - moistening apparatus comprises a wiper in the form of a roller 41 of suitable absorbing material, which roller is loosely mounted upon a stud 42 carried by a link 43, the rear end of the link being in hinge-connection with the long-arm of a lever 43^a. This lever is fulcrumed to an ear of a bracket 44 that projects from the top-portion of the adjacent standard, the short-arm of the lever 43^a being beveled at its end and disposed in the path of a tappet-rod 45, 60 which rod depends from the head of the

plunger, and is guided at its end in an apertured lug of the bracket 44. The beveled end of the short-arm of lever 43^a is held in contact with the end of the tappet-rod by a coil-spring 46 fast to an ear of the standard 70 and a pin carried by the long arm of said lever, which arm is preferably held against side-play by a looped guide-rod 47 fast to the said standard.

As shown in Fig. 2, the parts being in their 75 normal position, the moistening-roller 41 rests in water-pan 48, which is secured to the base upon the forward side of the anvil, the upper edge of the pan adjacent said anvil being approximately upon the same plane as 80 the latter, whereby the roller may be readily withdrawn from its immersed position in said pan for the purpose of distributing moisture upon a stamp in its travel.

In the operation of my device a strip of 85 stamps having their gum-side upward is inserted under the cover-plate 40, and pushed forward until the edge of the first stamp enters between the drum and spool. The operator then revolves the drum by turning the 90 hand-button 26 so as to bring the first stamp directly under the die-block. Thereafter the stamps are fed automatically one by one with each operation of the plunger, it being understood that when one strip of stamps has been 95 nearly exhausted another strip may be attached to the end of the first strip by an adhesive paper tape so that the feeding will be practically continuous. A stamp being upon the die-block the operator pushes the plunger 100 downward until said plunger is momentarily arrested by its end coming into contact with said die-block, this check in the stroke being well defined by reason of the added resistance of the two die-block springs. The initial 105 downward movement of the plunger caused the tappet-rod 45 to act immediately upon the lever 43^a swinging the same outward at its lower end, which action draws the moistening-roller over the gummed surface of the 110 stamp. The roller will now remain upon the opposite side of the anvil (as indicated by dotted lines in Fig. 2) until such time as the plunger has practically returned to its normal 115 position, owing to the fact that the tappet-rod impinges against the beveled end of the short-arm of the lever and holds said lever outward. Simultaneous with the above described action, the plunger rack-teeth have caused rotation of the train of gears by imparting a partial rotation to the pinion 12, the shoe of which pinion is now resting upon the smooth face of the plunger-extension. This reverse movement of the gear-train however has had no effect upon the feed-mechanism 125 which has remained stationary, while the pawl 23 of said gear-train has slipped upon ratchet-face 22 of the drum.

When the several parts are in the position as just described and being arrested in the 130

downstroke of the plunger, the operator will insert the envelop or card in position upon the stamp and thereafter continue the downstroke of the plunger, thus causing the stamp 5 to be severed from the strip by carrying the die-block downward with said plunger, which die-block also firmly affixes the stamp to the article by pressure from above. The said article is then removed. The plunger 10 and die-block are then immediately returned by their respective springs to their normal position, the return action of said plunger causing the gear-train to rotate in a reverse direction from that previously described, and 15 by means of which the drum is caused to rotate, owing to its ratchet-face 22 being engaged by the pawl 23, thus feeding another stamp forward and permitting the return of the moistening-roller to the water-pan.

20 While I have described a complete mechanism for carrying out the various movements for accomplishing the desired result; it is understood that the described structural details may be varied within the knowledge 25 of skilled-mechanics whereby similar movements essential to the invention can be obtained.

I claim:

1. A stamp-affixing device comprising a 30 base having standards, the base being provided with an anvil-portion and shearing-plate, a vertically disposed spring-controlled plunger guided between the standards, rack-teeth carried by the plunger, a stamp-feeding mechanism disposed rearward of the anvil-portion of the base and shearing-plate, a gear-train connecting the feed-mechanism and rack-teeth of said plunger, a vertically disposed spring-controlled die-block mounted 35 between said standards over the anvil-portion of the base and shearing-plate, a gear-train connecting the feed-mechanism and rack-teeth of said plunger, a vertically disposed spring-controlled die-block mounted 40 between said standards over the anvil-portion of the aforesaid base and arranged to be actuated by the aforesaid plunger, a knife carried by the die-block, the knife being

aligned with the shear-plate, a moistening-pan in connection with the base forward of its 45 anvil-portion, an absorbing-roller arranged to normally rest in the tray, and means in connection with the roller adapted to be actuated by the plunger to cause travel of said roller across the aforesaid anvil-portion of 50 the base.

2. A stamp-affixing device comprising a base having standards, the base being provided with an anvil-portion and shearing-plate, a vertically disposed spring-controlled 55 plunger guided between the standards, rack-teeth carried by the plunger, a stamp-feeding mechanism disposed rearward of the anvil-portion of the base and shearing-plate, a gear-train connecting the feed-mechanism 60 and rack-teeth of said plunger, a vertically disposed spring-controlled die-block mounted between said standards over the anvil-portion of the aforesaid base and arranged to be actuated by the aforesaid plunger, a knife 65 carried by the die-block, the knife being aligned with the shear-plate, a moistening-pan in connection with the base forward of its anvil-portion, an absorbing-roller in lever-connection with one of the standards and 70 adapted to normally rest in the moistening-pan, and means in connection with the plunger for actuating the lever connecting the absorbing-roller, whereby the latter is caused to travel across the anvil-portion of the base 75 upon the initial downward movement of said plunger.

In testimony that I claim the foregoing I have hereunto set my hand at Marinette, in the county of Marinette and State of Wisconsin, in the presence of two witnesses.
